UNITED STATES PATENT OFFICE.

JOHN H. BAWDEN, OF FREEHOLD, NEW JERSEY.

MOLDING-FLASK.

SPECIFICATION forming part of Letters Patent No. 280,557, dated July 3, 1883.

Application filed May 24, 1883. (No model.)

To all whom it may concern:

Be it known that I, JOHN H. BAWDEN, a citizen of the United States, and a resident of Freehold, Monmouth county, New Jersey, have 5 invented certain Improvements in Molding-Flasks, of which the following is a specification.

My invention consists of certain improvements in molding-flasks, my invention consisting, mainly, of a plate or bar forming part of the upper portion or cope, or of the middle portion or cheek of the flask, and constructed to hold the sand in proper form, substantially in the manner described hereinafter.

15 In the accompanying drawings, Figure 1 is a vertical section of part of a molding-flask illustrating my invention, the upper portion or cope of the flask being elevated above the lower portion; Fig. 2, a general plan view, 20 drawn to a reduced scale, of the said cope; Fig. 3, a perspective view of part of one of the cross bars or plates of the cope, and Fig. 4 an enlarged perspective view of part of the 25 said plate.

25 My invention is of general applicability in molding wherever the sand in the cope or cheek has prominent projections, forming cores for the mold, and terminating in comparatively sharp edges.

30 I have selected for illustration a mold the mass of sand, B in which has deep and tapering indentations or recesses formed by packing the said sand against a pattern, A, having deep tapering recesses a, into which the sand 35 D of the upper portion or cope of the flask is packed, and from which the projecting masses of sand have to be withdrawn with the cope when the latter is elevated prior to the removal of the pattern. In other words, the 40 projections or ribs b are the cores of the mold, and these cores are carried by the cope.

It has been the practice in such cases as I have explained to use "gaggers" for maintaining the integrity of projecting tender cores 45 in molding. These gaggers, which are simple strips of metal, with bent or T ends, are embedded in the sand to keep it together, the gaggers being sometimes passed over the bars of the cope, at their upper ends, so as to support the cores in which they are embedded.

50 In preparing a mold of the character shown, or any other mold in which there are deep recesses in one part of the flask and projecting

cores on the other part, I combine with the cope or other part of the flask one or more 55 plates or bars, G, in which are numerous perforations, m, and at the edge dovetailed recesses f. Thus, in preparing the mold, Fig. 1, there is one of these plates G wherever a projecting rib or core b occurs, the plate extending downward into the recesses of the pattern, so that on packing the sand the latter will enter the perforations and the dovetailed recesses; hence on elevating the cope there will be 60 complete and compact cores, each being composed of part of one of the plates, and sand clinging to both sides, owing to the perforations, and to the lower edge, owing to the dovetailed recesses. If the core has to terminate in a comparatively sharp lower edge, as in 65 the present instance, I bevel the lower edge of the plate in the manner best observed in Fig. 4. In the present case, the lower edges of the plates are straight; but the shape of each plate will depend upon the requirements 70 of the cores, of which many different forms are used in molding, it being advisable to form the dovetailed recesses around the entire edge of that part of the plate which is embedded in the sand.

75 The plates or bars may in some flasks be carried by the middle section or cheek, instead of by the cope; or both cope and cheek may be furnished with said plates. In the present instance the cope has but three plates 80 G, as shown in the plan view, Fig. 2; but there are cases in which a single plate only will be required, or in which more than three 85 may be necessary.

I claim as my invention—

90 1. The combination, with a molding-flask, of a plate or bar having dovetailed recesses f at the edge, substantially as set forth.

2. A molding-flask plate or bar beveled at its edge and having dovetailed recesses at the 95 said beveled edge, substantially as described.

3. A perforated molding-flask plate or bar having dovetailed recesses at its edge, substantially as specified.

In testimony whereof I have signed my name 100 to this specification in the presence of two subscribing witnesses.

JOHN H. BAWDEN.
